SIGNAL TRANSLATING APPARATUS

Frank Massa, West Collingswood, N. J., assignor
to Radio Corporation of America, a corporation
of Delaware

Application November 30, 1936, Serial No. 113,475

1 Claim. (Cl. 179—109)

This invention relates to signal translating apparatus, and more particularly to horn loudspeakers employing electrodynamic drivers.

It is well known that for the reproduction of low frequencies, it is best to employ a loudspeaker having a large diaphragm in order to radiate acoustic energy with minimum distortion. On the other hand, for the reproduction of high frequencies, it has been found desirable to employ a loudspeaker having a small diaphragm in order to prevent the diaphragm from breaking up, since it is generally desirable to have the diaphragm vibrate as a piston so that subharmonics will not be generated. It has also been well recognized that a horn improves the radiation efficiency of a loudspeaker and for this reason many loudspeakers have been provided with horns.

Various proposals have heretofore been made to provide horn loudspeakers in which advantage is taken of the foregoing principles. According to some, two entirely separate speakers are provided, one especially for reproduction of low frequencies and another especially to reproduce high frequencies, and each feeding into a separate horn. This type of loudspeaker has the disadvantage of requiring separate field structures for each diaphragm, if of the electrodynamic type, and the further disadvantage that two separate horns must be employed. According to other proposals, loudspeakers have been formed with either a single diaphragm and a single horn or a multi-section diaphragm and a single horn in order to cover the entire frequency range. In such cases, the horn must of necessity be designed to be a compromise between a good low frequency horn and a good high frequency horn. According to still other proposals, a single diaphragm is employed to feed what is known as a compound horn, or two separate horns, one associated with the front surface of the diaphragm and especially designed for high frequency reproduction, and the other associated with the rear surface of the diaphragm and especially designed for low frequency reproduction. Here, again, a compromise must be struck to obtain good response over the entire audio frequency range because of the limitations imposed by the use of a single diaphragm. In general, the diaphragm is too large to give optimum high frequency performance and too small to give good low frequency performance. Moreover, since, as in conventional loudspeakers of this type, a single voice coil is employed, both high and low frequency currents must be fed into the same coil, and acoustical means must be provided for causing a proper division of frequencies

between the two horns. Another disadvantage of the single diaphragm type of compound horn loudspeaker is that while the diaphragm is radiating high frequency vibrations, it is simultaneously being supplied with low frequency currents which cause it to move through large, low frequency excursions as well. This dual movement usually produces distortion in the high frequency output.

The primary object of my present invention is to provide an improved horn loudspeaker which will be free from the aforementioned disadvantages characteristic of prior art loudspeakers.

More specifically, it is an object of my present invention to provide an improved horn loudspeaker which will provide improved overall performance over that which has heretofore been obtained from a single loudspeaker.

Another object of this invention is to provide an improved horn loudspeaker which has a higher power handling capacity than is obtainable from corresponding prior art loudspeakers of this type.

Still another object of my present invention is to provide an improved horn loudspeaker which is characterized by a minimum of distortion, and particularly by a reduction of phase distortion in the horn throat.

A further object of my present invention is to provide an improved horn loudspeaker in which the division of frequencies between the high frequencies and the low frequencies can be more accurately controlled than heretofore.

A still further object of my present invention is to provide an improved horn type electrodynamic loudspeaker in which a single field structure is employed to most efficiently supply flux for a plurality of armatures or driving coils.

It is also an object of my present invention to provide an improved horn type loudspeaker as aforesaid which is relatively compact in construction, economical to operate, and highly efficient in use over the entire audio frequency range.

In accordance with my present invention, I employ two separate vibrating systems, one for the high frequency region and one for the low frequency region. Specifically, I employ two separate voice coils and two separate diaphragms or cones, a large cone with a large voice coil for driving a preferably folded, low frequency horn and a small cone with a small voice coil for driving a straight axis, high frequency horn which may be nested within the low frequency horn, if desired. Thus, I can, without compromise between good high frequency reproduction and good

low frequency reproduction, independently choose a suitable cone and voice coil to provide most efficient low frequency performance and another cone and voice coil suitable to most efficient high frequency performance. I also employ a common field structure to supply flux to both voice coils and arrange it in such a manner that the flux in the air gap for the high frequency voice coil is more dense than that in the air gap for the low frequency voice coil, which is a condition that I have indicated in my copending application Serial No. 113,120 as being very desirable in order to obtain maximum efficiency at the higher frequencies. As a further feature of my present invention, I can feed only high frequency voltages to the high frequency speaker, and low frequency voltages to the low frequency speaker, dividing the power either electrically, acoustically, or in both ways. Such a division of power makes it possible to accurately control the "overlap region."

The novel features that I consider characteristic of my invention are set forth with particularity in the appended claims. The invention itself, however, both as to its organization and method of operation, together with additional objects and advantages thereof will best be understood from the following description of several embodiments thereof when read in connection with the accompanying drawings wherein

Figure 1 is a graph showing several efficiency curves and horn loudspeakers of the type under consideration.

Figure 2 is a central sectional view of one form of horn loudspeaker built according to my present invention.

Figure 3 is a similar view of another form of my invention.

Figure 4 is a similar view of still another and preferred form of my invention, and

Figure 5 is a circuit diagram showing one method of electrically dividing the power supplied to the voice coils.

In my aforementioned copending application, I have fully discussed the fundamental factors which limit the performance of electrodynamically driven horn loudspeakers and have therein shown two families of curves showing maximum possible efficiencies that can be realized at various frequencies under ideal conditions. The conclusions reached as a result of the analysis set forth in my said copending application are that the efficiency of an electrodynamic horn loudspeaker is dependent upon the product of the resistivity times the density of the material of the voice coil, that efficiencies at the lower frequencies are inherently high, and that at the higher frequencies, the efficiency is critically dependent upon the ratio of the voice coil mass to the mass of the remainder of the vibrating system.

Referring, now, more specifically to the accompanying drawings, and particularly to Figure 1, the curve A shows the maximum efficiency obtainable from a horn loudspeaker over a range of approximately 30 to 10,000 cycles and represents one of the curves of the family of curves referred to above in connection with my previously mentioned copending application. From the curve A, which represents ideal conditions and was plotted with a fixed flux density at the air gap and on the assumption that the horn impedance is matched to the cone or diaphragm impedance at each point in the range covered thereby, it will be noted that the effi-

ciency at the lower frequencies is very high and that it drops off gradually as the higher frequencies are approached. In actual practice, it is, of course, entirely impractical for the foregoing condition to prevail in a single horn, and, therefore, in order to approach this condition, a number of horns must be employed. The curve B represents the efficiency characteristic of the loudspeaker where the throat area of the horn is such that the horn impedance matches the diaphragm impedance at about 100 cycles. Here, it will be seen that the efficiency at the lower frequencies remains substantially the same up to about 200 cycles, after which the efficiency drops much more rapidly than in the case assumed for the curve A. Coming, now, to the curve C, this shows the efficiency of a horn loudspeaker having a relatively small throat area and the horn impedance of which matches the diaphragm impedance at about 7,000 cycles. In this case, it will be seen that the efficiency is quite low until about 700 cycles after which it also drops off but at a much slower rate than in the case of the curve B and more nearly like the curve A. It is obvious, therefore, that a combination of two separate diaphragms and two separate horns, one combination of which follows the curve B and the other of which follows the curve C, will provide a compound horn loudspeaker which will follow the curve B to the point P (at which the curves B and C intersect) for most efficient reproduction of the lower frequencies, and thereafter will follow the curve C for most efficient reproduction of the higher frequencies, thereby approaching more nearly the ideal curve A. It is upon this principle that the several modifications of my present invention now to be described in detail are based.

Referring, first, to Figure 2 of the drawings, I have shown a compound horn loudspeaker having a relatively long horn 1 formed of a plurality of concentric, reversely directed, tub-like sections 1a, 1b and 1c preferably arranged to expand substantially exponentially and adapted to particularly accentuate the lower frequencies within the audio frequency range, and a relatively short horn 3 nested concentrically within the horn section 1a and adapted to particularly accentuate the higher frequencies within the audio frequency range, the horn 3 being a straight-axis horn and being also preferably formed to expand substantially exponentially. The horn 3 is suitably held in place within the horn section 1a by means of a plurality of partitions 5 and 7 which are secured to both the horn 3 and to a lining member 9 which, in turn, is secured to the horn section 1a. A plurality of holes 11 and 13 are formed in the partitions 5 and 7, respectively, circumferentially therearound for a purpose presently to be described.

Secured to the inner end of the lining member 9 is an apertured frame or "dish-pan" 15 which flexibly supports a relatively large frustoconical diaphragm or other suitable vibratile member 17 provided with a cylindrical coil form 19 on which a conductive voice coil or armature 21 is wound in conventional manner. To the frame 15 is suitably secured an annular plate 23 of magnetic material which is united with a U-shaped yoke 25, as by welding or soldering, the yoke 25 having a central pole piece 27 riveted or otherwise suitably secured thereto, and a coil 29 serving to magnetize the pole piece 27 when energized. A ring 31, which is U-shaped

in cross-section and is made of non-magnetic material, such as brass or copper, for example, serves to connect the plate 23 with a second annular plate 33 of magnetic material, the plates 23 and 33 being in the same plane and being radially spaced from each other to provide an annular air gap 35 for the voice coil 21. The annular plate 33 is also spaced from the reduced end of the center pole piece 27 to produce a second air gap 37 which is concentric with the air gap 35 and receives a conductive voice coil or armature 39 which is suitably wound on a voice coil form 41 of a relatively small diaphragm 43 flexibly held against the rear of the horn 3 by a ring 45 which is interposed between the plate 33 and the horn 3.

It will be noted from the foregoing that the air gaps 35 and 37 are in series and that the flux coming from the central pole piece 27 passes through both of them, the flux density within the air gap 35 being weaker, however, than that in the air gap 37 by reason of the fact that the mean cross sectional area of the air gap 35 normal to the direction of flux is more than the corresponding area of the air gap 37. The voice coil 21 is large and preferably made of copper, while the voice coil 39 is small and preferably made of aluminum (although either could also be made of the other material under certain conditions) in accordance with the teachings of my aforementioned copending application wherein I have pointed out that the efficiency of any system such as herein described is dependent, among other things, upon the density-resistivity product of the material of the voice coil. It is for this reason that I choose materials of different density-resistivity products for the voice coils 21 and 39.

The relatively large voice coil 21 is designed to be particularly responsive to low frequencies and serves to drive the large cone 17, which, in turn, feeds into the large horn 1 which has a relatively large throat area and the impedance of which may match the impedance of the cone 17 at about 100-150 cycles. On the other hand, the relatively small voice coil 39 is designed to be particularly responsive to high frequencies and serves to drive the small cone 43 which feeds into the small, high frequency horn 3, the latter having a small throat and having an impedance which matches the impedance of the cone 43 preferably in the range between 2000-7000 cycles. In this way, the efficiency of the entire system may be made to follow closely along such curves as the curves B and C of Fig. 1.

In order to insure a proper electrical division of energy between the voice coils 21 and 39 when they are fed from a common source of audio frequency signals, the current therefrom may be fed through a low pass filter 47 to the coil 21 and through a high pass filter 49 to the coil 39, as clearly shown in Fig. 5. Further control of the range to be reproduced through the horn 1 may be controlled by the aforementioned openings 11 and 13 in the partitions 5 and 7 which not only serve to establish communication between the cone 17 and the horn 1 but which may be suitably proportioned to constitute a low pass acoustic filter which will give the low frequency horn 1 a cut-off at some predetermined frequency which has been found desirable. At the same time, the cut-off frequency of the high frequency horn 3 due to its flare may be arranged to fall near the frequency at which the division of electrical energy as shown in Fig. 5 is made. Thus,

it is possible to fairly critically control the overlap region between the horns 1 and 3, and particularly so since the rings 31 and 45 prevent air displacements set up by either the diaphragm 17 or the diaphragm 43, upon vibration thereof, from reaching the other one. At the same time, by closing off the chamber or cavity behind large cone 17, as by means of a wall 51, this chamber may be made to resonate with the cone 17 at a frequency below the lowest frequency to which it is responsive (or to a frequency not appreciably thereabove), whereby the low frequency system described will have a substantially flat response characteristic throughout its entire working range.

In Fig. 3, I have shown a system which is very similar to that shown in Fig. 2. In the modification of Fig. 3, the horn 1 is provided with an additional, innermost section 1d to which the small horn 3 is directly secured at the front end with the small end of the horn 3 held against its throat 3a supported within the section 1d by a plurality of bracket members 53. The small cone 43 is flexibly supported against the throat 3a, as in the modification of Fig. 2, by the ring 45, while the large cone 17 is flexibly supported between a ring member 55 and the frame 15.

The magnetic structure of the modification under consideration comprises a drumlike member 57 of magnetic material to which are secured the plates 59 and 61, also of magnetic material and corresponding respectively to the plates 23 and 33 of Fig. 2, each of the plates 59 and 61 being provided with a plurality of circumferentially spaced apertures 63, whereby communication is established between the rear surface of the cone 17 and the chamber 65 between the small horn 3 and the horn section 1d. This chamber may be made to resonate with the cone 17 in a manner previously described in connection with Fig. 2 to provide a substantially flat response characteristic for the low frequency system.

The central pole piece 27 is held in place by a pair of ringlike members 67 and 69 of non-magnetic material, each firmly engaging the central pole piece 27 and being suitably secured to their respectively associated plates 59 and 61. Like the rings 31 and 45 of Fig. 2, the rings 67 and 69 of Fig. 3 serve to prevent air displacements set up upon vibration of either of the cones 17 and 43 from reaching the other.

It will be noted that the plate 59 is considerably thicker than the plate 61 and that the central pole piece 27 is of much smaller diameter at the end adjacent the horn 3 than at its other end. Since the air gaps 35 and 37 are again in series, it will be obvious that the flux flowing through the air gap 37 is necessarily much more dense than that flowing through the air gap 35. This is a condition necessary to greater efficiency at the higher frequencies and can be very easily realized in a construction such as that described by reason of the fact that the central pole piece 27 is common to both air gaps.

In Fig. 4 of the drawings, I have shown another modification of my invention wherein a plurality of high frequency horns 3 are employed in order to obtain greater spread of the high frequencies. The horns 3 preferably expand exponentially and are substantially straight axis horns, having only very slight bends therein in order to effect a proper distribution of the vibrations emanating therefrom over a large area. The smaller ends of the horns 3 are supported in a cup-shaped supporting member 71 within which the throats 73

3a of the horns 3 may be fitted, a frame member 13 serving to flexibly hold the small cone 43 against the throat 3a. The arrangement of the field structure for supplying flux to the air gaps 35 and 37 may be similar to that already described in connection with Fig. 3 and therefore is not believed to require further explanation.

From the foregoing description, it will be apparent that I have provided an improved form of compound horn loudspeaker wherein it is not necessary to compromise between either good low frequency or good high frequency performance, the large diaphragm 17 with its copper voice coil feeding the low frequency, large-throat, folded horn 1 most efficiently, and the small diaphragm 43 with its aluminum voice coil feeding the high frequency, small-throat, straight-axis horn most efficiently. By employing the large cone 17 in the manner described, I am able to obtain not only greater low frequency efficiency, but also increase power handling capacity and lower distortion, while the use of the small cone 43 as the high frequency driver enables me to obtain not only greater efficiencies at the high frequencies, but an extended high frequency range and a reduction of phase distortion in the throat of the high frequency horn 3 (or horns 3, as the case may be) as well. Due to the use of separate voice coils for the low and high frequency units, it is possible to divide the audio frequency supply electrically between the two speaker components, as fully described heretofore. This permits a definite control of the frequency division between the two systems. The use of an acoustic filter further enables better control of the division of the reproduced frequencies, and an acoustic filter of the type described in connection with Fig. 2 may, obviously, also be employed in connection with the

modifications of Figs. 3 and 4. I also wish to point out that the use of filters such as shown in Figure 5 in connection with the two separate speakers, as described will prevent low frequency currents being impressed on the high frequency voice coil 39 and the possible distortion which may occur in a single cone system in which the high and low frequencies are combined is entirely eliminated.

Although I have shown and described several modifications of my invention, I am fully aware that many further modifications thereof are possible and that many changes may be made therein without departing from the spirit of the invention. I, therefore, desire that my invention shall not be limited except insofar as is made necessary by the prior art and by the spirit of the appended claim.

I claim as my invention:

In signal translating apparatus, the combination of means providing a chamber, a relatively large vibratile member closing one end of said chamber, a driving coil particularly responsive to low frequencies associated with said large member, a relatively small vibratile member, a second driving coil particularly responsive to high frequencies associated with said small member, and means common to both of said coils for providing a magnetic field to coact with said coils, said means being so constructed and arranged as to provide a serial flux circuit for both said coils and a more dense field for said second named coil than for said first named coil, and said chamber resonating with said large vibratile member in a region such that a substantially flat response characteristic is provided for said large vibratile member.

FRANK MASSA.
